UNITED STATES PATENT OFFICE.

HENRY CLAY McCONNELL, OF GRAND RIVER, IOWA.

TRAIN-OPERATED GATE.

1,421,512.

Specification of Letters Patent. Patented July 4, 1922.

Application filed March 8, 1921. Serial No. 450,545.

To all whom it may concern:

Be it known that I, HENRY C. McCONNELL, a citizen of the United States, residing at Grand River, in the county of Decatur, State 5 of Iowa, have invented a new and useful Train-Operated Gate; and I do hereby declare the following to be a full, clear, and exact description of the invention, such as will enable others skilled in the art to which 10 it appertains to make and use the same.

The invention relates to train operated gates and has for its object to provide a device of this character which is opened and closed, through the medium of cables connected to pivoted lever, with which levers 15 the train while moving in either direction engages, for closing and opening the gate.

A further object is to provide a train operated gate and cable mechanism for operating 20 the gate, said cable mechanism being operated for closing the gate by pivoted levers located remotely in relation to the gate and on each side thereof and to provide lever and cable means adjacent the gate whereby 25 the gate will be opened immediately the first car or the engine of the train reaches the crossing.

A further object is to provide a lever and cable gate operating mechanism, operated by 30 a train, said mechanism being adapted for use in connection with a pivoted arm gate or a lazy tong gate.

With the above and other objects in view the invention resides in the combination and 35 arrangement of parts as hereinafter set forth, shown in the drawings, described and claimed, it being understood that changes in the precise embodiment of the invention may be made within the scope of what is 40 claimed without departing from the spirit of the invention.

In the drawings:

Figure 1 is a view in elevation of the gate and a portion of a railroad track.

Figure 2 is a top plan view of the gate and a portion of the railroad track.

Figure 3 is a sectional view on line 3—3 of Figure 1.

Figure 4 is a vertical longitudinal section 50 al view through one of the pivoted levers.

Figure 5 is a perspective view of another form of the invention, showing the use of a pivoted arm gate.

Referring to the drawings, the numeral 1 55 designates a portion of a railroad track and 2 a crossing. Disposed adjacent one side

of the track 1 is a post 3, which supports the gate 4. Gate 4 is a lazy-tong gate and has its end 5 pivotally secured as at 6 to brackets carried by the post 3, there being 60 a pin and slot connection 7 and 8 to allow freedom of movement of one of the rear bars of the lazy tong, thereby allowing the lazy tong as a whole to fold inwardly. Pivotally secured on lugs 9 carried by supports adjacent the side of the railway 1 and at points remote to the posts 3 and on each side thereof are horizontally movable levers 10, the arms 11 of which are provided with right angled portions 12 which are engaged by a 70 member carried by the engine, and preferably by the cow catcher for operating the mechanism hereinafter described. The levers 10 are returned to a right angled position in relation to the track after each gate operation, by means of coiled springs 9^a, one end of which is secured to the levers at 9^b and the other ends to the supports at 9^c.

By referring to Figures 1 and 2, it will be seen that a train has passed over the 80 track 1 in the direction of the arrow *a* and has rocked the lever 10 on its pivotal point thereby imparting a pull on the wire 13, which wire extends through a conduit 14, and over a pulley 15 pivotally mounted on 85 the post 3 and has its end secured as at 16 to a plate 17. Also secured to the plate 17 is an upwardly extending cable 18, which cable passes over a pulley 19 carried by the post 3 and has its end secured as at 20 to 90 the eye of the pin 21 of the lazy tong. Cable 18, at the time that a pull is imparted to the cable 13, is also moved and pulled downwardly and the lazy tong forced open to the position shown in Figure 1. It is obvious 95 that it will be essential to operate and throw the lazy tong gate to the position shown in Figure 1 when a train is moving in the direction of the arrow *b*. To accomplish this result, the cable 22 which 100 passes through the conduit 23 adjacent the side of the track also passes over a pulley 24 carried by the post 3 and has its end connected as at 25 to the plate 17. Thus it will be seen that when the lever 10 is moved 105 by the train, when the train is going in the direction of the arrow *b* that the cable 22 will be moved in such a manner that the cable 18 will be pulled downwardly, thereby opening the lazy tong so that it will extend across the crossing 2. To fold the lazy 110 tong gate inwardly a lever 26 is pivoted ad-

ja cent the post 3 as at 27 and has an up-
standing end 28 which is engaged by the
engine when it reaches the crossing. When
the lever 26 is rocked in either direction; a
5 pull will be imparted on a cable 29 which
passes between the pulleys 30, thence up-
wardly over the pulley 31 and has its ends
secured as at 32 to a plate 33, which is lo-
cated adjacent the spaced rollers 34. Con-
10 nected to the plate 33 and extending over
one of the rollers 34 and over the pulley 35,
is a cable 36, the end of which is secured
as at 37 to the eye of the bolt 21. Also con-
15 nected to the plate 33 is a cable 38 which
cable passes over one of the pulleys 34 and
has its ends connected to the plate 17. After
the tongs have been moved to the position
shown in Figure 1 by the train approaching
20 the crossing, it will be seen that the plate
17 has been moved to a point adjacent pul-
leys 15 and 24 and the plate 33 to a point
adjacent the spaced pulleys 34. During the
upward movement of the plate 33, cable 29
25 is straightened and pivoted lever 26 moved
to a right angled position in relation to
the railroad track 1, therefore when the train
is practically on the crossing 2, it will rock
the pivoted lever 26 and impart a pull on
30 the cable 29, cables 36 and 38. This action
of the cable 36 will cause the lazy tong
gate to be contracted inwardly and at the
same time cable 38 will pull upwardly on
the plate 17 and restore the pivoted levers
35 to normal position at right angles to the
track 1. It will be seen that no matter
which way the train is going, that only one
lever 10 will be in operative position, and
that the other lever will be moved out of
40 position where it will be engaged by the
train.

Referring to Figure 5, it will be seen
45 that the cables 13 and 22 extend over the
rollers 15 and 24 and are secured to the
plate 17^a, and that the cable 26^a carried by
the restoring lever 26 passes over a pulley
27 and thence over a pulley 28 and has its
end secured at 29 to the plate 17^a. It will
be seen that after a downward pull has been
imparted to the cable 39 which passes over
50 the pulleys 40 and is connected as at 41
to a pivoted gate 42, that said gate will be
pulled downwardly to the horizontally dis-
posed position shown in Figure 5, and the

plate 17^a to the lowered position shown in 55
Figure 5. Pivoted arm 42 is pivoted to
the post 3 as at 43, and is provided with
the weighted end 44, which weighted end
when strain is released on the cable 39 suf-
ficiently counterbalances the arm 42 so that 60
when all strain is released from the cable 39,
said arm under the influence of the weighted
end 44 moves to a vertical position. How-
ever to sufficiently relieve the strain on the
cable 29, the engine when it approaches the 65
crossing engages the lever 26 thereby im-
parting a pull on the cable 26^a. This ac-
tion causes the plate 17^a to move upwardly,
thereby relieving the strain on the cable 39
and allowing the pivoted arm 40 to pivot 70
upwardly to a substantially vertical position.

From the above it will be seen that a
cable controlled and train controlled cross-
ing gate is provided which is simple in con-
struction and positive in its operation and
one which may be cheaply constructed. 75

The invention having been set forth what
is claimed as new and useful is:—

A train operated gate, said gate comprising
80 a lazy tong supported by a post and hori-
zontally disposed, cables having their ends
secured to the lazy tongs adjacent their rear
pivotal point, one of said cables passing rear-
wardly over a pulley and downwardly over 85
a pulley and leading to an operating lever
adapted to be engaged by a train, the other
cable leading away from the supported end
of the lazy tongs and over a pulley and
downwardly and to a lever located remo-
90 tely from the post and adapted to be operated
by a train, a lever pivoted adjacent the post
and adapted to be operated by a train, a
cable connected to said last named lever and
95 passing between horizontally disposed pul-
leys and upwardly and having its end con-
nected to the rearwardly extending cable
and forming means whereby upon a down-
ward pull on the same the lazy tongs will be
folded. 100

In testimony whereof I have signed my
name to this specification in the presence of
two subscribing witnesses.

HENRY CLAY McCONNELL.
